BLOUSE

John Barile, Holliswood, N.Y., assignor to Andrea Blouse & Sportswear Company, New York, N.Y., a corporation of New York

Filed Jan. 30, 1963, Ser. No. 73,373

Term of patent 3½ years

(Cl. D3—25)

Fig. 1.

FIG. 2

FIG. 1 is a front elevational view of a blouse, showing my new design; and

FIG. 2 is a rear elevational view of the same.

I claim:

The ornamental design for a blouse, substantially as shown.
